UNITED STATES PATENT OFFICE.

MARIANO SALAS, OF CANLUBANG, LAGUNA, PHILIPPINE ISLANDS.

MOWER.

Application filed July 30, 1924. Serial No. 729,157.

The primary object of this invention is to provide a mowing machine for use on rail-ways for mowing the grass and weeds from between the rails of a track and from a strip 8 along each side of the track.

Another object of the invention is to pro-
vide a truck for carrying the mowing at-
tachment and which is arranged to engage
the rails of the track and which is provided
10 with a motor for propelling the same and for
actuating the cutting knife or knives.

A further object of the invention is to pro-
vide means for raising the knife carrying part
when the mower is not to be used.

15 This invention also consists in certain other
features of construction and in the combina-
tion and arrangement of the several parts, to
be hereinafter fully described, illustrated in
the accompanying drawings and specifically
20 pointed out in the appended claims.

In describing my invention in detail, refer-
ence will be had to the accompanying draw-
ings wherein like characters denote like or
corresponding parts throughout the several
25 views, and in which:—

Figure 1 is an elevation of the invention.

Figure 2 is a plan view.

Figure 3 is a plan view of the tiltable frame
which carries the mower mechanism.

30 Figure 4 is an enlarged plan view showing
a portion of the cutting means and the cy-
lindrical cam for operating the same.

Figure 5 is a section on line 5—5 of Fig-
ure 4.

35 Figure 6 is a section on line 6—6 of
Figure 5.

Figure 7 is a sectional view through the
combined pulley and clutch.

Figure 8 is a view of the driving means
40 from the motor to the rear shaft.

Figure 9 is a view of the means for shifting
the clutch member of said driving means.

In these views, 1 indicates a wheeled truck,
the wheels of which are designed to engage
45 the rails 2 of a track so that the device can
be used on railroad tracks, electric car tracks
and the like. A motor 3 is carried by the
truck and the shaft of the motor is connected
by the gears 4 with a vertical shaft 5, which
50 has a beveled pinion 6 at its lower end for
engaging either one of a pair of beveled
gears 7 which are slidably mounted on the
rear axle of the truck and which are movable
by the links 8 which are connected with the
55 hand lever 9. Thus the truck can be driven
in either direction by the motor or by moving

the gears 7 to a neutral position the truck
can be freed from the motor. A shaft 10 is
horizontally arranged adjacent the front end
60 of the truck and a framing consisting of the
arms 11 is pivotally mounted on said shaft.
The arms are spaced apart by the sleeves 12
and a combined pulley and friction clutch
13 with which is associated the sprocket 14
65 is mounted on said shaft, ball bearings 15
being arranged between the sprocket and the
small sleeve to take up thrust. A belt 16
passes over the pulley and over a pulley 17
on the motor shaft. A hand lever 18 is con-
70 nected with the pulley by means of the links
19 so that said pulley can be shifted into and
out of engagement with the clutch part to
which the sprocket is connected. The rod 20
to which the levers 9 and 18 are pivoted has
75 arms 21 thereon which engage grooves 22
in the extended part of the outer arms 11 so
that when the shaft is rocked by means of the
hand lever 23 the frame formed by the arms
11 will be tilted so as to place the mower
80 parts in operative or inoperative position,
as shown in full or dotted lines in Figure 1.
An L-shaped supporting member 24 is bolted
to the flanges 25 on the outer ends of the arms
11 and this member forms a support for a
85 T-bar 26, blades 27 to which the cutter bar
28 is fastened and a driving bar 29 which is
fastened to the cutter bar. The supporting
member also carries the wear plate 30 for the
blade and a plate 31 is fastened to the pro-
jecting part of the T-bar and extends down
90 close to the blade for acting as a shield for
the cutter bar and rear part of the blade.
The usual plate guide and cutter bar protec-
tor 32 are fastened to the T-bar and the
outer edge of the supporting member. The
blade is reciprocated by means of a cylinder
95 33 which is carried by a shaft 34 which has
the sprocket 35 thereon which is engaged by
a chain 36 which passes over the sprocket 14
and this cylinder has a cam groove 37 there-
in which engages a ring-like roller 38 on a
100 projection 39 of the driving bar 29 which
also has a ring-like roller 40 thereon for en-
gaging a slot 41 formed in the T-bar. Thus
as the cylinder is rotated the cam groove act-
ing upon the roller 38 will give reciprocating
movement to the driving bar which in turn
moves the cutter bar and the knife blades so
that the cutting edges of the knives co-
105 operating with the fingers formed on the
supporting member will cut the weeds and
grass between the rails and in a strip at the

110

outer sides of the rails. A deflector 42 is provided for the mowing parts for covering the same and for deflecting the grass and weeds cut by the knife to each side of the track. As 5 will be seen the driving bar, the cutter bar and the knife blade are formed in sections which are spaced apart to receive the rails when the mower is in lowered position. Small wheels 43 are carried by the outer parts of the 10 frame 11 for engaging the rails and act as rolling supports for the mower frame.

From the foregoing it will be seen that I have provided a simple arrangement of parts 15 for cutting the weeds and grass between the rails and at each side of a track. The apparatus is mainly intended for use in tropical countries where the weeds grow abundantly and considerable labor is required to keep them cut. The stubble left by the machine 20 acts to prevent the ballast from being washed out by heavy rains and by cutting the weeds the decay of the track parts is checked as they can quickly dry out after rains.

It is thought from the foregoing description 25 that the advantages and novel features of my invention will be readily apparent.

I desire it to be understood that I may make changes in the construction and in the combination and arrangement of the several 30 parts, provided that such changes fall within the scope of the appended claims.

What I claim is:—

1. A mowing apparatus, comprising a

truck having its wheels arranged to engage the rails of a track, a frame pivoted at the 35 front of the truck and extending downwardly, a supporting bar at the front of the frame formed in sections, with one section between the rails and the others at the outer sides of the rails, cutting means carried by each section of the bar, rollers on the frame for engaging the rails, a motor on the truck, means for propelling the truck from the motor, means for actuating the cutting means from the motor and manually operated means for 40 45 tilting the frame.

2. An apparatus of the class described comprising a truck, a motor thereon, means for propelling the truck from the motor, a shaft carried by the truck, a combined clutch and 50 pulley on the shaft, a belt for connecting the motor with the pulley, manually operated means for shifting the clutch parts, a sprocket connected with a clutch part, a frame pivotally mounted on the shaft, and having rear extensions thereon, cutting means at the front end of the frame, an actuating member for the same, a sprocket associated with the actuating member, a chain connecting the 55 sprockets, track engaging wheels carried by the frame, a shaft, arms thereon engaging the rear extensions of the frame and a hand lever connected with the shaft for tilting the same.

In testimony whereof I affix my signature.
MARIANO SALAS.
